ATTORNEYS.

UNITED STATES PATENT OFFICE

160,176

ALPHABET FOR FORMING MONOGRAMS
OR THE LIKE

Eugenie J. Jones, Webster Groves, Mo.

Application July 28, 1950, Serial No. 11,458

Term of patent 14 years

(Cl. D64—12)

To all whom it may concern:

Be it known that I, Eugenie J. Jones, a citizen of the United States, residing in Webster Groves, St. Louis County, Missouri, have invented a new, original, and ornamental Design for an Alphabet for Forming Monograms or the like, of which the following is a specification, reference being had to the accompanying drawing, forming a part thereof.

The drawing illustrates an alphabet for forming monograms or the like, showing my new design.

I claim:

The ornamental design for an alphabet for forming monograms or the like, substantially as shown.

EUGENIE J. JONES.
